UNITED STATES PATENT OFFICE.

BENJAMIN L. HEACOCK, OF READING, PENNSYLVANIA, ASSIGNEE TO THE SCHULTZ
UNDERWEAR COMPANY, OF READING, PENNSYLVANIA, A CORPORATION OF PENN-
SYLVANIA.

UNDERGARMENT.

1,062,398.

Specification of Letters Patent. Patented May 20, 1913.

Application filed August 5, 1912. Serial No. 713,231.

To all whom it may concern:

Be it known that I, BENJAMIN L. HEACOCK, citizen of the United States, residing at Reading, in the county of Berks and 5 State of Pennsylvania, have invented certain new and useful Improvements in Undergarments, of which the following is a specification.

This invention relates to improvements in 10 undergarments and it is intended more particularly for drawers and union suits worn by children.

The object of the present invention is to provide a garment, the lower ends of the 15 legs of which will have the appearance of a loose ruffled leg portion, while at the same time the leg end is securely closed. In other words, the object is to effect the combination of a so-called "bloomer" and 20 "ruffled" drawer leg.

The invention is intended more particularly for use by children, especially when made of knitted goods, and is intended primarily to overcome the slipping up of the 25 leg portions. It is of course applicable in all cases where short skirts are used, and where the security of the bloomer drawers is desired in connection with the more dressy effect of a ruffle.

30 The invention is more fully described in the following specification and clearly illustrated in the accompanying drawing, in which:—

Figure 1 illustrates the front elevation of 35 a pair of drawers showing my invention, one leg portion of which is open and the other closed or contracted by the tie string. Fig. 2 shows one garment leg, with a portion of the ruffle cut away, and the end 40 closed by the tie string. Fig. 3 shows a modified form, in which an elastic band is used in the place of the tie string.

The numeral 1 designates the body portion and 2 the leg portions of a pair of 45 drawers. The leg portions are provided

with means, preferably in the form of tie strings 3, for closing the lower ends of the legs and securing them to the leg of the wearer, so that they will not slip thereon.

At a point in close proximity to the lower 50 edge of each leg portion, I secure a ruffle 4, of any suitable material, and of such a length that when the tie strings are secured, thus drawing the lower ends of the legs against the leg of the wearer and forming a 55 bloomer, these ruffles will depend below the line of the closed portion and present the effect of a straight, loose, ruffled garment.

If desired, the tie string 3 may be replaced by an elastic band 5, as shown in 60 Fig. 3, thus overcoming the necessity of securing it.

It is evident that the present invention may be applied to garments made of different material, but it is intended more particularly for knitted goods, in which the tendency, especially with children, is to creep up 65 the leg while at play. With my invention, the leg portions are made secure and at the same time the appearance is that of a ruffle 70 finished garment.

Having thus fully described my invention, what I claim and desire to secure by Letters Patent is:—

In an undergarment of the class described 75 comprising a body portion and two relatively short leg portions, each of said leg portions having in its lower extremity means for contracting the same, and a ruffle attached to the outside of each leg portion in 80 close proximity to its contracted end, said ruffles depending below the line of said contracted ends.

In testimony whereof I affix my signature in presence of two witnesses.

BENJAMIN L. HEACOCK.
